UNITED STATES PATENT OFFICE.

FRANK S. BURT AND CLYDE L. ROWE, OF CHICAGO, ILLINOIS, ASSIGNORS TO QUICK-EDGE SHARPENER CO., OF CHICAGO, ILLINOIS, A CORPORATION OF ILLINOIS.

GRINDING-MACHINE.

1,184,517.

Specification of Letters Patent. Patented May 23, 1916.

Application filed September 17, 1915. Serial No. 51,254.

To all whom it may concern:

Be it known that we, FRANK S. BURT and CLYDE L. ROWE, both citizens of the United States, residing at Chicago, in the county of Cook and State of Illinois, have invented 5 certain new and useful Improvements in Grinding-Machines, of which the following is a specification.

This invention relates to a grinding machine for sharpening blades and performing similar work, and is concerned with a novel construction and arrangement of parts for accomplishing the grinding operations.

Our invention has for its objects the construction of a grinding machine which is simple, inexpensive, and durable, and which is otherwise fitted to fulfil the usual requirements of devices of this character; a grinding machine wherein the grinding surfaces 20 are so arranged with respect to the work as to insure effective action upon the work; a grinding machine having guides or holders for the work, and capable of adjustment with reference to the particular size or shape 25 of the work, and capable also of yielding to meet the requirements of the work.

The invention consists further in numerous other features of construction and combinations of parts as will more fully herein- 30 after appear.

In the drawing: Figure 1 is a plan view of a grinding machine constructed in accordance with our invention; Fig. 2 is a side elevation of the machine, looking toward the 35 side upon which the manual operating means is situated; Fig. 3 is a side elevation of the machine, looking upon the reverse side to that shown in Fig. 2; and Fig. 4 is a diagrammatic perspective view showing the 40 relation of the grinding surfaces to the work.

The present grinding machine comprises a hollow frame 5 from the lower end of which two shoulders 6 and 7 project laterally, a thumb screw 8 being threaded through the latter of these shoulders. This construction 45 enables the framework to be secured adjacent the edge of a table, shelf, or other fixed support, for the purpose of maintaining the machine stationary while the grinding operation takes place. Within the frame of the machine is journaled a toothed driving wheel 9, the shaft 10 of which extends through the frame. A crank 11 having 50 a handle 11^a is locked to the shaft 10,

and it is by this means that the driving wheel may be manually operated. Journaled within the hollow frame 5 are three other shafts 12, 13, and 14, each carrying a pinion, designated respectively as 15, 16, and 17. 60 The pinions 15 and 16 are each in mesh with the driving gear 9. The pinion 17 however is driven from the pinion 16 with which it is meshed, this arrangement enabling the pinions 15 and 17 to revolve in opposite directions when the driving wheel 9 is rotated. 65

The shafts 12 and 14 each extend through to the outside of the frame 5, being extended upon the side opposite the operating handle. Grinding wheels 18 and 19 respectively are secured to the ends of these shafts 12 and 14, being revolved in opposite directions when the driving wheel is operated. These grinding wheels are so arranged, moreover, as to overlap each other, this 70 clearly appearing from the several figures in the drawing. The form of these grinding wheels is such that a flat peripheral portion 20 is provided, and also a beveled peripheral portion 21. In the arrangement 75 shown, the beveled portions face inwardly and are in proximity to each other. Means for holding the work in grinding position are also provided, consisting of two arms 22 and 23, each bent generally in the form 80 of a semi-circle as appears best in Fig. 3. These arms are secured to the frame in any suitable manner, such for instance, as by screws 24, best shown in Fig. 3. The form 85 of these arms is such that they each lie outside of the shafts 12 and 14, and close to the overlapping surfaces of the grinding wheels secured to those shafts. We prefer 90 that the fastening means, such as the screws 24, should be slightly less in diameter than 95 the size of the openings in the arms 22 and 23 through which the screws pass, so that these arms may each be adjusted in any one of several positions within close limits, prior to tightening of the screws. The object and 100 purpose of this construction, which is shown by dotted lines in Fig. 3, will appear elsewhere in this specification.

The extremities 25 and 26, respectively, of the arms 22 and 23 are overlapped and inclined at substantially the same angle as the beveled edges of the grinding wheels. The form and material in which the arms 22 and 23 are made may be selected to impart to 105 them a certain amount of tension or resili- 110

ency. This is desirable as the work to be inserted between the guiding ends of these arms, and in operative position against the grinding wheels, requires that the arms 5 should yield sufficiently to accommodate work of various sizes and shapes. The tension exerted by the guiding ends of these arms serves manifestly to steady the work in position so that a proper grinding action 10 is insured. Where, for instance, a knife blade is to be sharpened, it is necessary that the blade be moved back and forth across the grinding surfaces of the wheels. In the construction we have shown, this back and 15 forth movement may be maintained in a substantially straight line between the guiding ends of the arms, and over the grinding surfaces of the wheels. In cases where the work requires that the guiding ends of the 20 arms should yield considerably, the screws 24 may be loosened, and the arms 22 and 23 be adjusted to a new position.

It will be noted, moreover, that the grinding wheels which we have shown not only 25 overlap each other, but are provided with beveled edges which face each other. The grinding action of a beveled edge upon the work is not comparable to that of a straight or flat edge. In the case of a beveled grinding 30 surface, there is developed a sidewise or lateral frictional engagement which assists materially in the grinding action.

It will be noted that each of the grinding wheels is provided with a flat peripheral 35 surface, as well as a beveled surface, and that a member 27 is shown extending adjacent the flat surface of the wheel 19. This is for the purpose of steadyng or holding work in position, which can best be acted 40 upon by a flat grinding surface rather than by a surface which is beveled.

From the description of our invention, it will be apparent that the present grinding machine is exceedingly simple of construction, and is well adapted to meet the requirements of devices of this kind. Obviously certain changes and modifications may be made from the precise construction which we have shown and described without in any 50 way departing from the scope of our invention.

We claim:

1. In a grinding machine, the combination with a frame, of companion grinding wheels 55 each formed with a beveled circumferential edge, said wheels being rotatably mounted upon the frame in overlapping adjacent positions with their beveled edges facing toward each other, means secured to the frame 60 for holding the work in operative position upon the wheels comprising a pair of arms

each provided with a guiding portion for the work disposed at an angle substantially the same as the beveled edges of the wheels, whereby the work is held between the wheels 65 in alinement with the beveled edges thereof, and means for revolving the grinding wheels simultaneously in opposite directions, substantially as described.

2. In a grinding machine, the combination 70 with a frame, of companion grinding wheels each formed with a beveled circumferential edge, said wheels being rotatably mounted upon the frame in overlapping adjacent positions with their beveled edges facing 75 toward each other, means secured adjustably to the frame for holding the work in operative position upon the wheels comprising a pair of tension arms each provided with a guiding portion for the work disposed at an angle substantially the same as the beveled edges of the wheels, whereby the work is held between the wheels in alinement with the beveled edges thereof, and means for revolving the grinding wheels 80 simultaneously in opposite directions, substantially as described.

3. In a grinding machine, a combination 85 with a frame, of companion grinding wheels each formed with a beveled circumferential 90 edge, said wheels being rotatably mounted upon the frame in overlapping adjacent positions with their beveled edges facing toward each other, means for holding the work in operative position comprising a pair of 95 arms secured to the frame, guiding portions on said arms disposed at an angle substantially the same as the beveled edges of the wheels, and arranged to retain the work therebetween in alinement with the beveled 100 edges of the wheels, and means for revolving the grinding wheels simultaneously in opposite directions, substantially as described.

4. In a grinding machine, the combination 105 with a frame, of companion grinding wheels each formed with a beveled circumferential edge, said wheels being rotatably mounted upon the frame in overlapping adjacent positions with their beveled edges 110 facing toward each other, means for holding the work in operative position upon the wheels in alinement with the beveled edges thereof, and means for revolving the grinding wheels simultaneously in opposite directions, substantially as described.
